BUFFER STRIP

Donald E. Mock, Covina, Calif., assignor to Anjac Plastics, Inc., El Monte, Calif., a corporation of California

Filed Mar. 13, 1963, Ser. No. 264,932

1 Claim. (Cl. 206—60)

This invention relates to an improved means for packing relatively flat items for shipping so that a plurality of such items may be packed together in a single carton or their shipping container without touching each other and accordingly without damaging each other. The invention more particularly relates to a buffer strip which can be installed around the edges of aluminum screens, aluminum glass windows, and aluminum framed sliding doors. The buffer strip firmly grasps the edge of such items and provides a space therebetween to prevent contact of such items with each other. So long as space is maintained between such items, they cannot bear upon each other and thus cause scratches or other damage.

In prior practice, such items have been packed with a plurality of items in a container and damage has been attempted to be prevented by insertion of a cardboard strip between the layers, or placement of a bent corrugated cardboard strip around the edges of such items. It might seem that such packing methods would be satisfactory. However, in modern shipping practice, cartons are subject to considerable vibration and shock and the cardboard strip materials soon slide out of the proper location for protection of the items packed in the carton. Similarly the strip bent around the edges of such items has no grasp thereupon and vibrates out of position.

Accordingly, it is an object of this invention to provide packing means which prevents damage upon each other by multiple items packed in a single carton.

It is a further object of this invention to provide a buffer strip which embraces the edge of a screen or the like and thus spaces it from another such screen packed in the same carton, thereby preventing damage of the screens upon each other.

It is a further object of this invention to provide a buffer strip for the packing of multiple screens in a single carton, which buffer strip is inexpensive and efficacious in preventing damage.

Further objects and advantages of this invention will become apparent upon reading the following specification and claim and the attached drawings in which:

FIGURE 1 is a perspective view of a plurality of screens showing the buffer strip of this invention installed thereon to prevent damage;

FIGURE 2 is a section taken along the line 2—2 of FIGURE 1;

FIGURE 3 is an end elevation of the buffer strip of this invention showing it uninstalled; and

FIGURE 4 is another species of my buffer strip shown in end elevation in the uninstalled position.

Referring now to the drawings, at 10 is shown a nest of screens, slightly expanded, ready for packing in a carton for shipment as a unit. These screens are manufactured of sheet material which is bent and rolled to the conventional configuration for such screens. Aluminum sheet 12 is formed into a screen having a front side 14 and a rear side 16. The front side 14 and the rear side 16 are respectively joined by rolled edges 18 and 20 between which is rolled a U-shaped channel 22 formed by the sheet material 12. Channel 22 is generally such that it has a bottom at right angles to the front and rear sides 14 and 16, respectively.

While aluminum screening is described herein, it is obvious that other screen materials can be used. Aluminum is desirable for this application because it is non-rusting and because it is easily worked and has an excellent ap-

2

pearance. Similarly, rather than a rolled structure such as is shown in FIGURE 2, the aluminum screening may be provided with extruded frames. The channel 22 is conventional in extruded frames as well, for it performs a function of permitting sliding, and in some types of applications it permits locking. This same type of frame structure is applicable, both in its rolled and extruded forms, to storm windows as well. Accordingly, while screens are discussed here, it is apparent that the invention does not confine itself to value only with respect to screens. Storm doors, storm windows, and screens as well as large sliding doors and sliding screens are equally well protected by this invention.

The buffer strip of this invention has an end wall 24 from which depend first and second side walls 26 and 28, respectively. The side walls 26 and 28 are joined by smooth curves to the end wall and are of substantially the same thickness. The first and second side walls extend at approximately right angles to the end walls 24. The extremities of both the first and second side walls 26 and 28 are arranged to turn angularly inward at 30 and 32 respectively. The edges 34 and 36 of the first and second side walls 26 and 28, respectively, are finished at right angles to the angular portions 30 and 32 respectively. This construction defines a generally U-shaped member, when taken in cross-section. The dimension between the insides of the first and second side walls 26 and 28 is such that the buffer strip can fit over the front and rear sides, 14 and 16, of the screen. First and second webs 38 and 40, respectively, are located on the inside of end wall 24. These webs stand from the end wall 24 into the inside of the generally U-shaped configuration of the buffer strip. The first and second webs are capped and connected by a section 42 having the shape of a chord and partial circumference of a circle. The length of the chord is greater than the distance across the first and second webs 38 and 40, and thus the cap section extends over the webs to provide retaining corners 44 and 46. When the buffer strip is installed upon the edge of a screen, as shown in FIGURE 2, the first and second webs 38 and 40 lie within the channel 22 of the edge of the screen, and the first and second walls 26 and 28 lie outside of the front and rear sides 14 and 16 of the screen. The retaining corners 44 and 46 are deformed within the channel 22 to provide a strong retention of the buffer strip upon the edge of the screen.

The buffer strip of FIGURE 4 is identical to the one shown in FIGURES 2 and 3 with the addition of ribs 48 and 50 to the first and second side walls 26 and 28. The buffer strip of FIGURE 4 accordingly provides more space between the screens upon which it is applied. This is useful in cases where there is hardware on the screen. Of course, it is most applicable in cases where doors are being shipped because these more usually have factory installed hardware extending from the sides thereof. The buffer strip of FIGURE 4 has ribs 48 and 50 of such dimension as to space such screen doors for adequate protection thereof.

The buffer strips of both FIGURES 3 and 4 are made of elastomeric material. This material may be of plastics or elastomeric type, or rubber. The material should be of such character as to have a substantial resistance against set so that it continues to tend to return to its unstressed shape. This shape is shown in FIGURES 3 and 4. This buffer strip is of such configuration that it may be easily extruded, and the material chosen should be of extrudable nature to obtain the benefit of this economic advantage, however, this method of manufacture is not critical for the strip could be formed by injection molding, or the like.

In use the material is cut from the extruder when it reaches relatively long length. In this condition it is

placed in the area in which it is to be installed, and is cut up into relatively small lengths. Of course longer lengths could be used along the edges of the screen, but relatively short lengths, as shown in FIGURE 1, are satisfactory. Alternatively the buffer strips could be chopped into relatively short lengths at the extruder, and moved to the place of use in random packed cartons. The buffer strips are installed by slipping them over the edge of the screen, and pressing them into place. The configuration of the buffer strip is related to the edge of the screens as they are being prepared to be packed in a carton. The proper number to be installed depends on experience, which is based upon the rigidity and length of the sides of the screen. In some cases it may be desirable to place buffer strips on every screen. In this situation, about half as many would be installed on each screen and spaced thereon in such manner as to give maximum support and protection.

In summary, this invention contemplates a buffer strip particularly suited for interior attachment to the edges of flat building hardware, such as screens, storm windows, storm doors, screen doors and similar articles. The purpose of the attachment of the buffer strip to those articles is to protect them in the final stages of manufacture, during finished part storage, and shipping, during storage and display by the dealer or jobber, and during shipment to the job site until the final installation. With such protection the articles are unmarred at the time of installation. The buffer strip has an end wall to protect the edges of the article, side walls to protect the sides of the article and retaining means to hold it on the article.

Applicant having particularly pointed out the preferred embodiment of his invention in this specification, it is apparent to those skilled in the art that numerous modifications and changes can be made within the scope of this invention. Accordingly, the scope of this invention is defined by the following claim.

I claim:

The combination of a buffer strip and building hardware;

said building hardware having first and second sides, said first and second sides each terminating at an edge, said first and second sides being substantially planar adjacent said edges, a channel formed in said building hardware between the edges thereof, said channel having a channel bottom, said channel bottom being positioned between said sides and away from said edges;

said buffer strip being made of elastomeric material, said buffer strip comprising:

a substantially planar end wall, said end wall having first and second edges and first and second sides,

said second side of said end wall having substantially planar form between said first and second edges; first and second side walls integrally formed with said end wall on said first side at said first and second edges of said end wall, said first and second side walls extending away from said first side of said end wall so that when said buffer strip is installed upon said edge of said building hardware, said first and second side walls are elastically deformed to extend angularly away from each other for a first distance from said end wall, said first and second side walls extending angularly toward each other from said first distance to the extremities of said first and second side walls so as to resiliently engage said building hardware adjacent said extremities and so as to define a structure having a generally U-shaped cross section;

first and second webs integrally formed on said first side of said end wall, said first and second webs being positioned away from said first and second side walls and extending away from said end wall between said first and second side walls, said first and second webs extending into said channel in said building hardware between said edges thereof and extending toward said channel bottom, a cap integrally formed with said first and second webs, said cap extending from said first web to said second web, and extending past said webs to define retaining corners, said retaining corners resiliently engaging within the interior of said channel so as to retain said buffer strip on said building hardware; said end wall, said first and second webs and said cap thus defining a hollow space to permit flexure of said webs and said cap so that said first and second side walls and said retaining corners resiliently engage said building hardware to retain said buffer strip in position on said hardware while said end wall protects said edges of said hardware and said first and second side walls protect said sides of said hardware.
